FIG.3

FIG.5

FIG.1

FIG.2

FIG.4

FIGURE 1 is a front elevational view of a tote waste receptacle or similar article showing our new design;

FIGURE 2 is a side elevation thereof as seen from the right of FIG. 1, the side opposite being similar except devoid of the recessed area in the lower wall thereof;

FIGURE 3 is a top plan view thereof;

FIGURE 4 is a bottom plan view thereof; and

FIGURE 5 is a partial and enlarged cross-sectional view taken along line 5—5 of FIG. 3.

This is a continuation-in-part of design application Ser. No. D.4,469 of Oct. 31, 1966, which is a continuation of design application Ser. No. D.83,957 of Feb. 24, 1965, both of which are now abandoned.

We claim:

The ornamental design for a tote waste receptacle or similar article, as shown and described.
